UNITED STATES PATENT OFFICE

WALTER L. DIXON, OF BOSTON, MASSACHUSETTS, ASSIGNOR TO REECE FOLDING MACHINE COMPANY, OF BOSTON, MASSACHUSETTS, A CORPORATION OF MAINE

INFOLDING MACHINE

Application filed February 27, 1931. Serial No. 518,702.

This invention is a novel infolding machine, and relates more especially to the infolding of the margins of blanks composed of cloth or analogous material, for example blanks used in the manufacture of articles 5 of apparel and other similar articles. The principles of the present invention are herein shown applied to a machine in which the blank defining and blank folding elements are designed for the production of a relatively small shape, typically represented as of circular outline, although various other shapes may be folded, such small folded shapes having various uses, for example for the pads or connecting portions of men's garters, which, due to their small size present substantial problems in the accurate infolding and pressing thereof. It is desirable in any folded blanks composed of cloth or the like that the infolds should not only be accurately formed over a defining member or templet, but should be effectively squeezed and pressed in their folded condition, so as to maintain their shape until combined or stitched into the final article. This condition presents difficulties due to the smallness of the shape, the practical difficulty in providing a templet which will contract out of the folds before the pressing, and the desirability of effecting the pressing after the folds have been disengaged by the defining member.

In my copending application Serial No. 273,694, filed April 28, 1928 there is disclosed an infolding machine for small shapes or garter pads, the same having means for infolding and outfeeding the blanks and a particular form of templet or die which, notwithstanding the small size, is adapted to contract out of the folds, so as to disengage the blanks in advance of the squeezing thereof and their removal from the bed of the machine. Such a templet embodies a complication of delicate parts and for that reason is not wholly satisfactory, besides which the principles of templet construction shown in said application are not available for all possible shapes of small size blanks.

The principal object therefore of the present invention is to afford an infolding ma-

chine which, in an efficient manner, and with a large rate of output, will infold and press blanks of small size, without the need of a templet of the contracting type; although the principles hereof might in some cases be combined with the principles of templet contraction. A particular object of the present invention is to provide, in the machine of the class referred to, a combination of defining, infolding and pressing means, automatically 65 operated, wherein at one stage of operation the infolders may move in upon the work to form the infolds as defined by the templet, and at another stage, after the templet has been extracted from the folds, but without 69 dislodging the blank upon the bed, the infolders are moved inwardly again upon the work and thereupon take part in a pressing operation by which the folds are squeezed between the infolders and the bed. Other and 73 further objects and advantages of the present invention will be apparent to those skilled in the subject of infolding machines of the class referred to.

To the attainment of objects and advantages recited the present invention consists in the novel infolding machine and the novel features of combination, arrangement, construction, method and operation herein illustrated or described.

In the accompanying drawings Figure 1 is a right elevation of a folding machine embodying the present invention.

Fig. 2 is a top plan view, with the front of the machine at the near side of the figure, and 85 with certain parts broken away to show other parts more clearly.

Fig. 3 is a right elevation view partially similar to Fig. 1, on an enlarged scale, showing in fore-and-aft section parts of the templet, the infolders and the bed, with blanks resting upon the bed and infolders and the templet in act of descending thereupon.

Fig. 4 is a similar view showing the same parts in a later stage of operation wherein the templet has descended upon the blank upon the bed.

Fig. 5 shows a still later stage wherein the infolders have lifted above the level of the bed.

Fig. 6 is a similar view wherein the infolders have moved in, forming the infolds over the margins of the templet.

Fig. 7 in similar view shows a later stage wherein the infolders have retracted outwardly and the defining portion of the templet has lifted, while the blank holding part of the templet has remained upon the blank, holding it in position upon the bed.

Fig. 8 is a similar view at a later stage wherein the infolders have again moved inwardly, to reform the folds, and have been depressed forcibly to squeeze the folds upon the bed.

Fig. 9 is a bottom plan view of the templet showing its interior holding portion and the surrounding circular defining portion.

The several operative parts of the machine may be driven from a main or operating shaft 19 having its bearings in the two end upright portions of the general frame 20 of the machine. The frame at its upper portion supports a fixed plate or bed 21, upon which the infolding is performed, but preferably the center of the bed is slightly raised as shown at 22, forming an elevated surface or pedestal, below the top level of which the infolders may normally lie. The blanks are received and infolded on top of the pedestal or surface 22, the templet descending directly on to the blanks on the pedestal, and the infolders thereafter rising and moving inwardly to produce the infolds.

At the upper rear part of the frame are two brackets 24, the upper ends of which afford bearings for a longitudinal rock shaft 25 on which are fixed a pair of forwardly extending arms 26 carrying at their extremities the die or templet 27, which is thus fitted to be swung downwardly upon the bed and raised therefrom. The templet may be lowered and raised as in said prior application, there being shown a rear lever 29 attached to the shaft 25, and a connection or link 30 therefrom to the rear end of an arm 31 of a heavy bell crank lever, the other or upward arm 32 of which carries a follower or cam roll 33 held by the weight of the templet in contact with the periphery of a cam 34 mounted on the main shaft 19, the cam having a contour such as to cause the lowering and lifting movements of the templet in coordination with the infolding and pressing movements.

The blank B is indicated in Figs. 3 to 8 inclusive and may consist of a simple piece of cloth or similar material, of the same general shape but slightly larger than the defining part of the templet, which for illustrative purposes is shown as circular. The blank is shown in its initial or unfolded condition in Figs. 3 and 4, while in Fig. 5 the margins have been turned up by the lift of the infolders and in Fig. 6 turned in by the approach of the infolders. In Fig. 7 the folds have been released by the infolders and slightly reopened

by the extraction of the defining part of the templet. In Fig. 8 the blank has had its infolds again depressed and squeezed, so that the blank is ready for removal after being wholly released by the infolders and templet. 70

The infolding means is indicated in Fig. 2 and partially in Figs. 3-8, and the connections in Fig. 1. Owing to the circular outline of the particular blank used for illustration there may be two end infolders 35 and two side infolders 36 all of simple shape converging upon the blank as defined by the templet. Thus each infolder may include a quadrant of the shape to be folded. The entire infolder system may be carried bodily on a movable plate or table 37 on which they are confined by plates 38. Similarly the side infolders 36 are fitted in the table and confined by plates 39. The four infolders are thus readily slideable radially inwardly and outwardly. 75 20 25

Having thus described in a general way the character and location of the blank supporting bed, the infolding system, and the defining templet reference will next be made to the power operating connections for the main shaft, and thereafter the connections from the main shaft to the defining and infolding element. What may be termed a power shaft 42 is shown in Fig. 2, and this may be connected and disconnected from a source of power by a clutch means. The construction may be generally similar to that shown in the prior application, the shaft 42 carrying a worm which engages with a worm wheel 44 on the left end of the main shaft 19. The front end of the power shaft is shown squared at 45 to permit the machine to be operated manually by a crank. A single rotation of the main shaft 19 corresponds with a complete cycle of operations, and the power shaft may be motor driven at relatively high speed such for example as to produce thirty cycles or completed blanks per minute. 100 105 110 115 120 125

Referring next to the operation of the end infolders, an actuating shank 47 is shown for each of them, its inner end having a stud engaging with a recess in a block 48 attached directly on top of the infolder 35. Thereby the infolder may be moved inwardly and outwardly through the movements of the shank 47. At its outer end the shank 47 is adjustably connected to a block 49 and the block 49 has a downwardly extending shank or rod 50 which telescopes within a sleeve 51, these constituting an extensible lever having its fulcrum on an axle 52 below which extends an arm 53 carrying a follower 54 engaging within the groove 55 of a cam disk 56 as shown in Figs. 1 and 2. Thereby the rotation of the disk, carried by the shaft 19, causes the cam groove to operate through the described connections to move the infolder 35 inwardly and outwardly at each end of the machine. 130 135 140

As all of the infolders may move simultaneously, with the form of blank herein illustrated, a simple interconnection may be provided for the operation of the side infolders by the inward movement of the end infolders. Thus each end infolder is shown as having secured to it a plate 58 extending laterally and longitudinally to where a cam slot 59 is provided, cut for example at 45°, and engaged by a cam pin 60 standing up from a side infolder 36, the pin adapted to move radially in a slot 61 formed in the fixed confining plate 39. By this arrangement when the two end infolders are simultaneously thrust inwardly they operate through the cams 59 to force inwardly simultaneously the two side infolders. The infolders are all shown in their inward position in Fig. 2 and the side infolders are shown in various positions in Figs. 3-8.

The vertical movements of the table 37 carrying the infolding system are between the lowered position as shown in Figs. 3 and 4, the elevated position as shown in Figs. 5, 6 and 7, and the partly depressed or squeezing position as shown in Fig. 8. A means for effecting the up and down movements of the infolder system is herein indicated to the extent of the downwardly extending connectors or links 66 arranged adjacent to the four corners of the table 37, as appears in Fig. 1. The further connections by which these means are lifted and lowered are not herein shown, inasmuch as such connections are shown in full in said prior application, commencing with the four downwardly extending links 66, having the same reference number as herein, and the trains of connection 66-93 whereby the rotation of the main shaft effects the coordinated lifted and lowering and pressing movements of the infolder system in a manner to carry out the steps already described. The bodily upward and downward movements of the infolder system are permitted by reason of the telescoping character of the connection 50-51 by which inward and outward movements are communicated from the cam 56 to the individual infolders.

The die or templet 27 is mounted at the front ends of the carrying arms 26, said arms having extensions 95 beneath which is directly attached a heavy frame plate or body 96 on which the defining and other parts of the templet are mounted.

With this invention the requirement of contraction of the templet to extract it from the folds may be dispensed with, and a non-contractible or so-called solid templet is shown, supported beneath the body 96. Thus, extending downwardly from the body 96 is shown a depending post or leg 97, attached to the body 96. The post 97 may be generally cylindrical, with a shoulder in contact with the under side of the body, and a reduced diameter extending through an aper-

ture in the body, with screw threads formed at the upper end, and an attaching nut 98 employed rigidly to secure the post to the body. The post 97 is preferably hollow, having a longitudinal bore 99 through its upper portion, with an enlarged bore or chamber 100 at its lower portion, these accommodating the movable part to be described. At the top of the post is an apertured end 101, with its aperture relatively reduced or restricted in diameter, to form a guide, and similarly the bottom end of the post at 102 may have a reduced opening for similar purposes.

The actual blank defining plate 103 is shown attached by screws 104 to the bottom end of the post 97, as seen in bottom view in Fig. 9. By this arrangement the templet plate 103, which defines the folds, and which for illustration is shown circular, is a non-contractible defining plate mounted in fixed relation to the templet body, so that its only movement is a downward and upward swinging movement about the axle 25 as a center. The templet plate 103 is shown centrally cut away to receive the holder plate about to be described.

The holder plate 106 of the templet is mounted so that it may occupy the cut out area within the defining plate 103, and it is formed with wings 107 which overlap the underside 102 of the post 97.

The holder plate 106 is shown occupying the cut out portion of the defining plate 103 in Figs. 4, 5 and 6, this being the relative position of the two plates when the defining plate rests upon the blank. At other times the holding plate stands relatively lower than the defining plate, sometimes bearing upon the blank to hold it against displacement, as seen in Figs. 7 and 8, and sometimes elevated above the bed, as shown in Figs. 1 and 3, to permit the extraction of folded blanks and insertion of unfolded ones.

As an additional feature the holder plate 106 hereof is shown as provided with a downwardly standing surface or projection 108, shown in the form of a circular disk, and serving to impress or emboss a design upon the finished blank. For example the plate 108 may be a concentric circle considerably smaller than the outline of the finished blank, and the underlying bed or pad 22 may be formed with a corresponding sink or recess 23, above which the material may initially lie, as seen in Fig. 3, and into which it is depressed to form the embossing or design, as seen in Figs. 4 to 8. It is to be understood that the elements taking part in the operations upon the blank may be maintained in heated condition, for example by heating the bed and pad, so as to assist preserving more efficiently the infolded and embossed condition of the blank.

The templet holding member 106, and the

embossing attachment 108, are shown attached by screw 109 to a block or carrier 110 mounted to slide through the aperture 102 during the relative movements of the holding plate. The carrier block 110 is shown formed at the lower end of a stem 112 slidable in the aperture 101 at the top of the post 97. This shank also may have a rocking movement in passing through said aperture, for which reason the aperture may have rounded edges as indicated in Fig. 4.

While the carrier block 110 and its shank 112 may be of various sectional shapes, they are herein indicated as circular in section. The carrier or block 110 however has its surface elements 111 out of alignment with the length of the shank, and indeed at a distinct slant, so that in the relative movement of the carrier through the lower end of the post the carrier and shank are shifted or swung laterally, as will be best seen by comparison between Figs. 3 and 4. Stated differently, the carrier 110 has surfaces 111 constituting cams which, when shifted longitudinally effect a relative lateral movement. By reason of this feature it is insured that when the templet, with the post 97 and the defining plate 103 lift slightly, for example from the position of Fig. 6 to the position of Fig. 7, the holding plate 106 will not be displaced relatively to the bed and the blank thereon. The incline of the cam sides of the carrier 110 is determined by drawing an imaginary line from the axis of the axle 25, about which the templet swings, to the approximate center of the carrier 110, and laying out the slanting edges at a right angle or tangent thereto. Looking at this feature in another way, and considering the holder and carrier as temporarily in fixed position upon the blank overlying the bed, the defining plate 103 and its post 97 are swung upwardly on an incline, due to the substantial elevation of the axle 25 above the level of the bed, and the slanting contour of the carrier sides 111 accommodates this slanting movement of the defining plate and post, so that as the latter rise and swing leftwardly as seen in Figs. 6 and 7 they move along the predetermined slant, and thus avoid actual displacement of the carrier and holding plate. During this movement the carrier and its shank swing relatively within the hollow interior of the post; while absolute movement thereof is positively prevented.

When the operations are completed, and the templet is to be lifted bodily, the holding plate must be raised with the defining plate, and for this purpose the upper end of the shank 112 is shown threaded, and fitted with a pair of interlocking stop nuts 113, determining the relatively lowered position of the holding plate, as seen in Fig. 3. It is important that relative rotation of the shank 112 and carrier 111 be prevented, when these are

circular in form, and for this purpose a radius arm 115 is shown attached by a screw device 116 to the upper part of the shank 112, above the stop nuts 113, this radius arm extending rearwardly, or to the right in Figs. 3 and 4, where it has secured to it a depending shank 117 slidable through an aperture formed at 70 118 in the templet body 96, there being a guide plate 119 mounted on the body 96, which guide plate confines the shank 117 against lateral movement while permitting certain fore-and-aft movement or play during the relative tilting of the holding plate shank 112. 75

In order to hold the holding plate 106 down upon the blank during the rise of the defining plate, instead of relying upon gravity, a spring or resilient device may be used. Thus bearing down upon the top end of the shank 102 is shown a bar 121, slidable near its free end between a pair of upright guides 122 mounted on the templet body, and pivoted at its left end to a pair of upright standards 123. A spring 125 is arranged to pull down constantly upon the bar 121 so that the resilient pressure is communicated to thrust the shank 112 and the holding plate carried thereby relatively downward to the position as shown in Figs. 1, 3, 7 and 8. 80

The supply of blanks to, and the removing of them from, the bed may be generally similar to the feeding means as shown in said prior application, this operation being preferably automatic rather than manual. In connection with the feeding operations the machine is shown provided with a forwardly extending shelf 142 arranged to hold piles of raw blanks so that the operator can manually supply them to the infeeding elements with convenience and rapidity. Inset in the shelf 100 is a position plate 143, indicative of where the infeeding element is positioned when retracted, this plate having an upstanding gage or cleat 144 to receive and center the shank 105 of the infeeding device as it comes down in its outward or retracted position. 110

The infeeding carrier 146 corresponds in shape and size to the unfolded blank, which for example may be circular. It is in the nature of an open tray or rack within which the successive blanks may be set by hand, and through the bottom of which the blanks may pass in the folding position. The infeeder has a stem 147 connected to a curved arm 149 arranged to oscillate rearwardly and forwardly to carry the infeeder to and from in-folding position. The rear end of the arm 149 is formed with hubs 150 engaging an axle mounted at the top end of a plunger or rod 153 capable of vertical sliding movement and 115 rotation. 125

In each cycle the infeeder 146 lifts bodily to clear the gage 144 and then swings rearwardly to infolding position over the pad 120 125 130 135 140 145 150 155 160 165 170 175 180 185 190 195 200 205 folders, while after the infolding and removal of the templet the infeeder again rises and then swings outwardly and descends into initial position.

- 5 The up and down movements may be effected by lifting and lowering the plunger 153, the lower end of which is connected by a stem 158 with the forward end of a cam lever 160, the lever carrying a follower 162 engaging the groove 163 of a cam disk 164 mounted on a counter shaft 165. The contour of the groove 163 is such as to effect the properly timed lifting and lowering movements of the infeeding device.
- 10 15 The rearward and forward movements of the infeeder 146 may be effected by the following connections. The plunger 153 is shown as fitted within an oscillating sleeve 166, the upper end of which has an extending arm 167. Above the arm 167 the plunger has a similar arm 168 and these two arms are connected by a pin 169, so that oscillation of the sleeve will bodily swing the plunger and feeding devices. The sleeve 166 is rotatable within outer guiding sleeves 170 and 171, the sleeve 166 carrying a rock arm 172 by which it may be oscillated. The rock arm 172 has a suitable loose connection with a cam lever 174, the follower 176 of which engages the peripheral groove 177 in the cam disk 164. By the cooperation of the two cams in the disk 164 the swinging, lifting and lowering movements of the feeding devices are effected. The cam disk 164 is rotated uniformly with the main shaft 196, by a pair of meshing gears of equal size, as shown in said prior application.

30 35 The outfeeding member is shown as a suction nozzle 179 mounted on the swinging end 40 of a carrying pipe 180. This pipe may be supported by the same hub device 150 that carries the infeeding arm 149 so as to partake of the up and down and as well the rearward and forward movements of the infeeding device. The outfeeding device however, which is shown in its blank engaging position in Figs. 1 and 2, is adapted, after lifting the blank by suction from the bed to swing rearwardly and release or discharge the blank into a suitable receptacle arranged behind the bed. The alternate suction and pressure required for the picking up and the discharging of the blank may be supplied by means of a hose 182 extending to the pipe 180 55 from a pneumatic cylinder 184, the piston 185 of which is reciprocated through a rod 186 connected to a crank or pin 187 mounted for convenience on the cam disk 56; the cylinder being pivoted at 188 to permit the swinging of the cylinder during the rotation of the crank. By this arrangement the piston is reciprocated within the cylinder, producing first the necessary suction, followed by the compression of air for the purposes of outfeeding the successive infolded blanks.

The prior application may be referred to for any details of construction and operation which are not herein fully described because forming no essential part of the novelty of the present application. For example the timing of the various cams, cranks etc., and the resulting operations, are fully indicated in the prior application, except for such obvious differences as are necessary to carry out the successive operations herein indicated.

70 75 Generally speaking the operation of the present invention is in accordance with the successive illustrations, in which Figs. 1, 2 and 3 may be considered to represent the initial position, with the templet elevated and the infolders retracted and lowered, this also representing the final position, preparatory to the commencement of a new cycle; while the intermediate positions, or the important ones of them, are illustrated by the successive figures or diagrams 4 to 8 inclusive.

80 85 Commencing with the position of Fig. 3, wherein a fresh blank B has been fed upon the bed or pedestal 22 the operations may be as follows. It will be understood that in Figs. 3 to 8 the infeeding and outfeeding devices have been omitted, to simplify the showing of the novel features hereof, as indeed they might be omitted in case of manual positioning of the blanks upon the bed and removal therefrom. As the main shaft makes a single rotation the following described operations take place. The templet first descends into defining relation upon the blank, as shown in Fig. 4. During this descending movement of the templet the holding plate 106 first contacts the blank upon the bed, and it thereupon relatively yields upwardly as the defining plate 103 completes its downward movement. The downward movement of the defining plate corresponds with the inclination of the sides of the block 110 carrying the holding plate. The result of this cooperation is that the holding plate first engages the center of the blank and maintains it steadily in position, while the defining plate comes down into defining relation. There is no lateral displacement of the holding plate during the descent of the defining plate, nor subsequently during the relative rise thereof.

90 95 100 105 110 115 120 125 130 Passing now from the Fig. 4 to the Fig. 5 position, the infolders 36, which have remained below the level of the pedestal 22, are bodily lifted to a level above the pedestal and above the templet plate overlying the same, as shown in Fig. 5. This motion is succeeded by the inward or folding movement of the infolders to the succeeding position as shown in Fig. 6, the margins of the blank being turned in over the margins of the defining plate, preliminarily forming the folded blank, which however is occupied by the non-contractible defining plate 103.

Instead of employing a contractible defining plate the operations of the present inven-

tion proceed as follows. Following the position shown in Fig. 6 the infolders 36 retract at all sides of the blank to a position corresponding with that shown in Figs. 5 and 7. 5 Preferably the infolders are retracted slightly beyond their normal outward position shown in Figs. 4 and 5, and Fig. 7 shows them somewhat withdrawn, giving a safe clearance for the next succeeding operation. As 10 soon as the infolders have thus cleared the outer edges of the folded blanks the templet is bodily lifted partially or to a slight extent, as indicated in Fig. 7, so that the defining plate 103 is elevated substantially above the 15 level of the blank and infolders. The defining plate slightly opens up the folds and snaps out of them, which is permitted due to the fact that the folds are freshly formed and not yet permanently creased. During this 20 elevating movement of the defining plate and the resulting removal of the same from the folds the blank itself is held firmly in position by the holding plate 106, which is forced relatively downward by its own weight and 25 spring 125. The blank thereby is prevented from being displaced. Fig. 7 shows the parts in this position, with the infolders temporarily retracted and the templet defining plate relatively lifted, in which position the defining plate is held until the completion of 30 the folding and pressing operations.

Following the Fig. 7 position the infolders are promptly moved inwardly over the 35 slightly opened up folds, as seen by comparison of Fig. 7 and Fig. 8. The folds are readily again turned in and down, the inturned margins being insufficient to overlap or conflict with the holding plate. When the infolders have thus again reached their inward position 40 they are bodily pulled downwardly for the blanksqueezing or pressing operation, and the folds are firmly and permanently pressed and creased by this action of the infolders forcing them against the heated bed or 45 pedestal. Fig. 8 shows the parts in this position.

Following the Fig. 8 position of the parts, and after a sufficient lapse of time for the 50 proper pressing of the blanks, the pressure of the infolders is relaxed, and they are slightly elevated and retracted to their outward position as shown in Fig. 7, and thereafter lowered and restored to their initial position as seen in Figs. 3 and 4. During 55 these return movements of the infolders the templet is caused to resume its lifting movement, passing from the position of Fig. 8 to the position of Fig. 3. This leaves the completely folded and pressed blank exposed 60 upon the bed. During the pause in which the templet remains in its elevated position the blank feeding devices may operate. The infolder 146, lying idly at the folding position, is swung forwardly to blank receiving position 65 as shown in Fig. 2, while the outfeeder

179 is swung forwardly to a position above the blank, whereupon suction is applied and as the feeding devices descend the blank is picked up by the suction, so that on the return swinging movement of the feeding devices the completed blank is carried rearwardly to the outfeeding point, while a fresh unfolded blank is brought rearwardly from the table 142 to the folding position. 70

In a certain aspect the present invention 75 may be viewed as one for a certain combination of elements in an automatic infolding machine operating in a certain way to afford the advantages and results hereinabove specified. The bed or pedestal constitutes a support for each blank to be infolded. The defining plate 103 of the templet may be described as a definer arranged to move into defining position upon the blank and to retract therefrom, namely by the movement of the templet toward and from the support. The holding plate 106 may be considered as a holder, also arranged to move into position upon a portion of the blank to hold the latter upon the support and to retract therefrom. 80 With these elements is combined infolding means arranged to infold the edge or edges of the blank upon the definer. The machine is operated by timed actuating means with connections to the definer, the holder and the infolding means such that the infolding means twice advances and retracts for each blank, while the definer between the first retraction and the second advance of the infolding means retracts away from the blank 85 while the blank remains held by the holder. This combination gives the advantages referred to and dispenses with the need of contraction of the defining part of the templet. Following the final retraction of the infolding means the holder retracts from the blank and therefrom the folded blank may be taken out and a fresh one inserted either manually or automatically. Other aspects of the invention and other combinations and subcombinations which are novel will be pointed out 90 in the claims. 95

While the blank holder and the blank definer are both mounted in cooperative relation upon the same templet they may, broadly speaking, be independently mounted but actuated, in accordance with the principles just set forth. It is preferable that they both be mounted on the templet, and relatively movable. While the holder might be fast 100 on the templet and the definer relatively liftable the reverse arrangement is preferred, as illustrated. The holder might be made use of to bring an unfolded blank into position 105 on the bed or subsequently to remove the completed blank from the bed. 110

It will thus be seen that there has been 115 described an infolding machine of the class referred to embodying the principles and attaining the objects of the present invention. 120

Since various matters of combination, arrangement, construction, method and operation may be modified without departing from the principles of the invention it is not intended to limit the same to such matters except so far as set forth in the appended claims.

What is claimed is:

1. In an automatic machine for infolding the edges of blanks of cloth, leather or the like, a support for the blank to be infolded, a definer arranged to move into defining position upon the blank and retract therefrom, a holder arranged to move into position upon a portion of the blank to hold the blank upon the support, and to retract therefrom, infolding means arranged to infold the blank edge upon the definer, and timed actuating means for said definer, holder and infolding means, such that the infolding means twice advances and retracts for each blank, and the definer between the first retraction and second advance of the infolding means retracts from the blank while the blank remains held by the holder.
2. In an automatic machine for infolding the edges of blanks of cloth, leather or the like, a support for the blank to be infolded, a definer arranged to move into defining position upon the blank and retract therefrom, a holder arranged to move into position upon a portion of the blank to hold the blank upon the support, and to retract therefrom, infolding means arranged to infold the blank edge upon the definer, and timed actuating means for said definer, holder and infolding means, such that the definer is moved to the support to define the blank, and thereafter the infolding means infolds the blank upon the definer and retracts, and thereafter the definer retracts from the blank while the blank is held by the holder, and thereafter the infolding means again operates to complete the infolding and retracts, and thereafter the holder retracts from the support.
3. In an automatic machine for infolding the edges of blanks of cloth, leather or the like, a support for the blank to be infolded, a definer arranged to move into defining position upon the blank and retract therefrom, a holder arranged to move into position upon a portion of the blank to hold the blank upon the support, and to retract therefrom, infolding means arranged to infold the blank edge upon the definer, and timed actuating means for said definer, holder and infolding means, such that the infolding means twice advances and retracts for each blank, and the definer between the first retraction and second advance of the infolding means retracts from the blank while the blank remains held by the holder.
4. In an automatic machine for infolding the edges of blanks of cloth, leather or the like, a support for the blank to be infolded, a definer arranged to move into defining position upon the blank and retract therefrom, a holder arranged to move into position upon a portion of the blank to hold the blank upon the support, and to retract therefrom, infolding means arranged to infold the blank edge upon the definer, and timed actuating means for said definer, holder and infolding means, such that the infolding means twice advances and retracts for each blank, first while the definer is in position upon the blank and second after the definer has been retracted from the blank and the blank remains held by the holder.
5. An infolding machine as in claim 1 and wherein after the second advance of the infolding means pressure is applied to squeeze the infolds between the infolding means and support.
6. In a machine for infolding the edges and embossing the middle of fabric blanks, a blank support, a blank definer, edge infolding means, and complementary means associated with the support and definer respectively for embossing a substantial area of the middle part of the blank, without penetrating the same.
7. An infolding machine as in claim 1 and wherein the support is recessed and the holder carries a projecting part cooperating therewith to form a depression or embossing on the blank.
8. In an automatic machine for infolding the edges of blanks of cloth, leather or the like, a support for the blank to be infolded, a templet movable toward and from the support, a definer carried by the templet and arranged to move into defining position upon the blank and retract therefrom, a holder carried by the templet and arranged to move into position upon a portion of the blank to hold the blank upon the support, and to retract therefrom, infolding means arranged to infold the blank edge upon the definer, and timed actuating means for said definer, holder and infolding means, such that the infolding means twice advances and retracts for each blank, first while the definer is in position upon the blank and second after the definer has been retracted from the blank and the blank remains held by the holder.
9. An infolding machine as in claim 8 and wherein the definer covers the margins of the area to be infolded and is interiorly recessed, and the holder covers the middle part of the area and is accommodated in such recess.
10. An infolding machine as in claim 8 and

wherein the templet has a depending post to which the definer is secured, and the holder is mounted on a separate shank shiftable longitudinally relatively to the post.

5 11. An infolding machine as in claim 8 and wherein the templet has a depending post to which the definer is secured, and the holder is mounted on a separate shank shiftable longitudinally relatively to the post, with
10 spring means pressing the holder from the definer, and a stop limiting such movement of the holder.

12. In an automatic machine for infolding the edges of blanks of cloth, leather or the like, a support for the blank to be infolded, a templet swingable toward and from the support about a rear horizontal axis, a definer carried by the templet and arranged to move into defining position upon the blank
20 and retract therefrom, a holder mounted movably upon the templet and arranged to move into position upon a portion of the blank to hold the blank upon the support, and to retract therefrom, and to yield toward
25 the definer as the templet brings the latter to the blank, infolding means arranged to infold the blank edge upon the definer, and timed actuating means for said definer, holder and infolding means; the definer having
30 a depending post by which it is connected rigidly with the templet and which post stands vertical in lowered position, and the holder having a shank by which it is connected yieldingly with the templet and which shank
35 is mounted for relative oblique motion upon the templet, whereby the holder may remain immovably upon the blank during relative movements of the templet and definer.

13. In an automatic machine for infolding the edges of blanks of cloth, leather or the like, a support for the blank to be infolded, a templet swingable toward and from the support about an axis removed from the plane of the support, a definer carried by the templet and arranged to move into defining position upon the blank and retract therefrom on an inclined path about said axis, a holder carried by the templet and arranged to move relatively thereon about said axis into position upon a portion of the blank to hold the blank upon the support, and to retract therefrom, infolding means arranged to infold the blank edge upon the definer, and timed actuating means for said definer, holder and infolding means, such that the infolding means twice advances and retracts for each blank, first while the definer is in position upon the blank and second after the definer has been retracted from the blank and the blank remains held by the holder.

14. An infolding machine as in claim 13 and wherein the holder is mounted on a shank slidable and tiltable in the templet, with cam means causing it to tilt relatively during relative movement, whereby it may hold a fixed

position on the blank during retraction of the defining member.

15. An infolding machine as in claim 13 and wherein the holder is mounted on a shank slidable and tiltable in the templet, with cam means causing it to tilt relatively during relative movement, whereby it may hold a fixed position on the blank during retraction of the defining member, and means preventing turning of said holder and shank during relative sliding movement.

16. In an automatic machine for infolding the edges of blanks of cloth, leather or the like, a flat support for the blank to be infolded, a definer arranged to descend into defining position upon the blank and lift therefrom, a holder arranged to descend into position upon a portion of the blank to clamp the blank upon the support, and to lift therefrom, an infolder arranged to infold the blank edge upon the definer, actuating means for lowering the definer and holder upon the blank, then moving the infolder in and out, then elevating the definer, then moving the infolder in and out and then elevating the holder.

In testimony whereof, this specification has been duly signed by:

WALTER L. DIXON.
